United States Patent Office.

JOSEPH BEAUMONT, OF CHAMBERSBURG, PENNSYLVANIA.

Letters Patent No. 79,188, dated June 23, 1868.

IMPROVED MANGLE.

The Schedule referred to in these Letters Patent and making part of the same.

TO ALL WHOM IT MAY CONCERN:

Be it known that I, JOSEPH BEAUMONT, of Chambersburg, in the State of Pennsylvania, have invented a new and useful Improvement in Mangles; and I do hereby declare that the following is a full, clear, and exact description of the same, reference being had to the accompanying drawings and letters of reference marked thereon, making a part of this specification, in which—

Figure 1 is a side elevation, showing the table extended.

Figure 2 is a plan view of the same with like view of the table.

Figure 3 is an end elevation, showing the spring-attachments.

This invention consists in the employment of adjustable brackets, in combination with other devices, to regulate the pressure of the cylinder of a mangling-machine, as will hereinafter more fully appear.

To enable those skilled in the art to make and use my invention, I now proceed to describe its construction and operation.

Similar letters in the drawings refer to like parts.

A represents an iron frame fifty inches high, or thereabouts, in which is supported a wooden cylinder, a, which may be five inches and a half in diameter and thirty inches long. In the side-pieces of the frame A, above and below the bearings of the cylinder a, are slots, b, two in each end-piece, in which slots are placed the journals of wooden cylinders, c c', of similar dimensions to the cylinder a.

The cylinders c c' are kept in contact with the cylinder a by means of coiled springs, c'', one end of each of which is connected with the journal of the cylinder, and the other end with an adjustable bracket, d, which bracket is connected with the frame A by means of set-screws. Of the brackets d there are two, one at each end of the frame. The cylinder c' is kept in contact with the middle cylinder by means of a similar arrangement of coiled springs, c''', and brackets, d'. By these means the distance between the middle cylinder and the upper or lower one may be increased or decreased at pleasure.

B represents a folding table hinged at one side of the frame A, so as to be turned up against the same, and folded or let down and extended. When it is in the latter condition, the table is supported by legs d''.

An enveloping-cloth, e, is tacked along one end to the surface of the cylinder A, and when extended will be spread out on the surface of the table B. The fabric to be smoothed is laid upon the folding-cloth as it lies thus spread out, and by means of suitable gearing the middle cylinder is turned so as to draw the folding-cloth and fabric with it inward between the lower and middle cylinder, and wind them both around said middle cylinder, the fabric being between the same and the enveloping-cloth, and consequently receiving a pressure, which tends to smooth it. This pressure is augmented by the action of the cylinders c c', which being forced asunder from the cylinder a by the intervention of the fabric and enveloping-cloth necessarily contribute to the smoothing of the material under pressure.

Having thus fully described my invention, what I claim as new, and desire to secure by Letters Patent, is—

The rollers a c c', in combination with the enveloping-cloth e, table A, adjustable brackets d d', and springs c'' c''', as and for the purpose described.
